UNITED STATES PATENT OFFICE.

ALEXANDER McDougall AND ALEXANDER MILLER McDougall, OF DULUTH,
MINNESOTA.

SEA-GOING CANAL-BOAT.

1,122,783.

Specification of Letters Patent. Patented Dec. 29, 1914.

Application filed July 15, 1912. Serial No. 709,457.

To all whom it may concern:

Be it known that we, ALEXANDER McDougall and ALEXANDER MILLER McDougall, citizens of the United States, residing 5 at Duluth, in the county of St. Louis and State of Minnesota, have invented certain new and useful Improvements in Sea-Going Canal-Boats, of which the following is a specification, reference being had therein to 10 the accompanying drawing.

Our invention relates to improvements in sea-going canal boats.

The object of our present invention is to provide a combination canal and sea-going vessel 15 in which the smoke stack, superstructures and all working parts above the upper deck can be readily removed and lowered within the hull of the vessel so as to enable the boat to pass under low bridges, such as 20 are found spanning ordinary canals.

Another object of our invention is to provide a vessel of this character in which the main or upper deck is straight and parallel with the keel of the vessel from stem to 25 stern, which adds materially to the longitudinal strength of the vessel and to its seaworthiness, and at the same time increases the carrying capacity thereof.

A still further object is to provide a simple 30 cheap and effective boat of this character having certain details of construction hereinafter fully set forth and claimed.

In the accompanying drawings Figure 1 is a side elevation of a self propelled sea-going canal boat embodying our invention. Fig. 2 is a longitudinal vertical sectional view of Fig. 1, showing the smoke stack, superstructures, and all working parts lowered within the vessel and below the main deck thereof. Fig. 3 is a top plan view of Fig. 2. Fig. 4 is a side elevation similar to Fig. 1, of a vessel not having its own motive power, but embodying our invention. Fig. 5 is a vertical longitudinal section of Fig. 4 showing the superstructures and working parts lowered within the hull of the vessel below the main deck thereof. Fig. 6 is a top plan view of Fig. 5. Fig. 7 is a cross sectional view of our improved vessel such as shown in Figs. 4, 5 and 6, looking 50 toward the stern. Fig. 8 is a side elevation of the bow of our improved vessel, partly broken away and showing means for raising

and lowering the forward superstructures, bollards, etc. Fig. 9 is a transverse sectional view of a canal, showing a bridge of low form and our improved boat passing thereunder.

Referring now to the drawings, 1 represents the hull of our improved double purpose vessel, having the straight upper deck 2, which is parallel with the keel from stem to stern of the vessel and provided with suitable hatches 14 for the handling of the cargo. This straight upper deck greatly strengthens the vessel longitudinally, as compared with the ordinary vessel made high at both ends and low amidships. It also materially increases the carrying capacity of the vessel and is the simplest and 70 cheapest possible form of construction.

The forward end of both steamer and barge is provided with a removable superstructure or turret 3 having a door 4 upon one side thereof, by means of which entrance 75 may be had to the turret. A hatch, not shown, may also be provided in the top of the turret whereby access may be had to the turret from the top in case of rough weather at sea, there being means of communication 80 with the interior of the hull through the hatch 16, as shown in Figs. 2, 3, 5 and 6 of the drawings. A suitable railing 5 is provided around the upper edge of the turret to protect the sailors, which is well understood. A capstan 17 is mounted upon the upper end of the turret 3 and is removably connected with the windlass 15 within the compartment 18 below the main deck 2 of the vessel.

As is understood, the windlass 15 has suitable steam connections whereby it may be power-operated and thus made to operate the capstan on top of the turret, for the handling of lines, etc., the anchor chains 95 being operated within the compartment 18, as clearly illustrated, and which operation of the windlass may be controlled either from the top of the turret when at sea, or from within the compartment 18 when navigating canals. Certain auxiliary line handling means accompany the windlass 15, such as suitable catheads, which are not shown but are common to such devices, and are made use of for handling lines through 100 the exterior walls of the compartment 105

18 when the vessel is being manipulated within canals and under bridges, and, these being operated through the cut-away portion of the bows of the vessel, allow of 5 ample and convenient manipulation of the same, even when the vessel is broadside against the side of the canal or lock. Two pairs of bitts or bollards are mounted upon the turret 3 fore and aft of the capstan, they being for the convenient handling of the 10 lines.

A compartment 20 is formed within the hull 1 directly abaft the compartment 18 and covered with a suitable hatch cover 10, 15 preferably the entire size of the compartment, as illustrated in Figs. 2 and 3 of the drawings. This compartment 20 is for the reception of the turret 3 in its entirety when removed from the deck 2 of the vessel when 20 the latter is required to pass under bridges in canal navigation.

In lieu of the compartment 20 we have illustrated in Figs. 4, 5 and 8 a platform or elevated floor 21 upon which the turret may be placed, if preferred to the compartment 20, the hatchway directly thereover and covered by the hatch cover 10, the same being equally necessary for the passage of the turret 3 in its entirety.

30 Bollards or bitts 6 are removably mounted upon the deck 2 of the vessel, preferably just forward of the turret 3 when the vessel is at sea, as shown in Figs. 1 and 4 of the drawings and which may be removed and placed within the compartment 18 when it is necessary to have the deck 2 clear of obstructions, as illustrated in Figs. 2, 3, 5 and 6.

A pilot superstructure or turret 11, similar to the turret 3 is removably mounted 40 upon the deck 2 of the vessel adjacent the stern thereof and, in the case of the steamer, just forward of the removable smoke stack 8, but, in the barge, somewhat farther aft, 45 as clearly illustrated, the steering wheel being indicated at 32. This turret is also provided with a door 7 therein and, when on deck, surmounts the hatchway 12 which communicates with the interior of the hull 50 of the vessel and, in the case of the barge, directly with the compartment 22.

Within the hull 1 of the steamer is formed a compartment 23 just forward of the hatch 12, for the reception of the turret 11, the 55 stack 8 and the life boats 25, the compartment being covered by the large hatch cover 24. We have illustrated a modification of the compartment 23 in the barge, Figs. 4, 5 and 7, in that we have shown a simple 60 platform 26 provided for the reception of the deck elements of the vessel when removed for storage thereupon, if such platform be found more practical. However, we prefer the inclosed compartment 23.

65 The smoke stack 8 is preferably made in

three sections one section within the hull and terminating approximately flush with the deck 2 whereby the remaining two sections may be fitted thereupon vertically and also conveniently removed and placed below 70 decks when occasion for such arises.

Bitts or bollards 9 are removably mounted upon the extreme after portion of the deck 2 and are arranged to be readily removed and placed within either the compartment 22, as in the barge, or in the compartment 13 in the steamer.

For convenient manipulation of the movable parts which are at times above the deck 2 and at other times below said deck, as 80 clearly illustrated, we provide portable shears 27 which are a convenient form of derrick for the raising and lowering of the various parts, the tackle 28 being suspended from the shears and readily attachable to 85 such parts as it is desired to remove.

Power for operating the tackle 28 is provided for in the form of suitable winches 29, housed within depressed wells 30 within the deck, one just abaft the hatch 10 and one just forward of the hatch 24, each well being covered with a suitable hatch cover, as is obvious. Thus, when it is desired to remove any of the movable parts of the vessel the hatch covers are removed from 95 the wells 30, the shear 27 erected and line connection made with the tackle 28 to the winch 29, whereby the desired results of lifting and adjusting of the various parts are obtained.

Upon the stern of the barge, illustrated in Fig. 4 of the drawings, we show one set of shears employed as a means of support for the life boat. The same may be so utilized at any time when the deck of the 105 vessel is not cleared away for canal navigation.

From the foregoing it is evident we have provided a practical double purpose vessel in which all of the parts above the uppermost deck of the vessel necessary in its navigation at sea, may be quickly and easily disconnected from the deck and lowered within the hull of the vessel, whereby the latter may be readily navigated within restricted 110 canals and pass under bridges with despatch.

Having thus described our invention, what we claim and desire to secure by Letters Patent is:—

1. A canal and sea-going vessel comprising a hull, portable turrets, bollards, and smoke stack carried by the vessel, portable means carried by the vessel for moving the portable parts of the vessel either in or out 120 of the boat.

2. A canal and sea-going vessel comprising a hull having a continuous straight deck forming the upper wall thereof, removable turrets and bollards upon the deck of the hull adjacent either end thereof, means car- 125

130

- ried by the vessel for removing the turrets and bollards and placing them within the hull of the vessel.
3. A canal and sea-going vessel comprising a hull having a continuous straight deck forming the upper wall thereof, removable turrets and bollards upon the deck of the hull adjacent either end thereof, adjustable shears carried by the vessel for removing the turrets and bollards and placing them within the hull of the vessel.
4. A canal and sea-going vessel comprising a hull having a continuous straight upper deck, removable turrets, bollards and smoke stack mounted upon the said upper deck for sea navigation, or below the said upper deck for canal navigation, and adjustable means mounted upon said deck for imparting such transformation.
5. A transformable vessel of the character described comprising a hull, having a straight flush upper deck from stem to stern, a plurality of turrets removably carried by the vessel, a plurality of removable bollards carried by the vessel, and means carried by the vessel for placing the turrets and bollards in their entirety either above or below the upper deck as the transformation requires.
6. A canal and sea-going vessel comprising a hull having a straight upper deck from stem to stern, removable means above the deck for controlling the vessel and its mooring elements, means below the said deck for controlling the vessel and its mooring elements and means carried by the vessel for removing the first mentioned controlling means and placing them within the hull of the vessel.
7. A canal and sea-going vessel comprising a hull having a straight upper deck from stem to stern, a removable turret upon the forward end of the vessel carrying a fixed capstan and bollards, a removable turret upon the after end of the vessel carrying steering elements, a removable sectional smoke stack abaft of the after turret, removable bollards upon both ends of the vessel and adjustable means carried by the vessel for placing all of the removable elements below the deck of the vessel when required.
8. A canal and sea-going vessel comprising a hull having a straight upper deck from stem to stern, a removable turret upon the forward end of the vessel carrying a fixed capstan and bollards, a removable turret upon the after end of the vessel carrying the steering elements, removable bollards upon the upper deck of the vessel and adjustable means carried by the vessel for placing all of the movable elements below the upper deck of the vessel.
9. A canal and sea-going vessel comprising a hull having an upper continuous deck the entire length thereof, a plurality of removable turrets mounted upon the said deck to assist in navigating the vessel while at sea, a plurality of mooring and towing bollards mounted upon the said deck, an adjustable derrick carrying hoisting elements and mounted upon the deck adjacent said turrets for the purpose of lifting the said turrets and bollards in their entirety into the hull of the vessel, depressed wells within said deck, line controlling winches within the wells, for imparting lifting power to the hoisting elements of the derricks.
10. A convertible vessel of the character described, comprising a hull having a continuous straight deck forming the upper wall thereof, removable turrets and bollards upon the deck of the hull adjacent the ends thereof, adjustable hoisting elements carried by the deck for removing the turrets and bollards and placing them within the hull of the vessel, power for operating the hoisting elements being derived from suitable mechanism below the deck.
11. A convertible vessel of the character described comprising a hull having a continuous straight deck forming the upper wall thereof, removable turrets and bollards upon the said deck, wells or compartments below the said deck adjacent the turrets and access thereto being had through the deck, wells containing winches, within the deck and adjacent the first mentioned wells or compartments, an adjustable derrick adjacent the turrets and carrying hoisting elements deriving their power from said winches, whereby the turrets may be removed and placed in the compartments and the bollards removed and placed below the said deck.
12. A convertible vessel of the character described comprising a hull having a straight deck forming the upper wall thereof, a removable turret at each end of the vessel and upon the deck thereof, removable bollards upon the deck of the vessel, a compartment within the hull adjacent each turret, means for removing each turret in its entirety and placing them within the compartments and also placing the bollards below the deck for the purpose described.
13. A convertible vessel of the character described comprising a hull having a continuous deck forming the upper wall thereof, a removable turret at each end of the vessel and normally resting upon the said deck, a sectional removable smoke stack abaft the after turret, removable bollards upon the said deck, depressed wells within the said deck adjacent the turrets, winches within the wells, adjustable hoisting means adjacent the turrets and deriving their power from winches, whereby the bollards, smoke stack and turrets may be lowered beneath the said deck, when desired.
14. A canal and sea going vessel of the character described comprising a hull hav-

ing a deck forming the upper wall thereof, a compartment within each end of the hull, mooring elements within the compartments for controlling the vessel when navigating the canals, removable superstructures above said deck for controlling the vessel when navigating unrestricted waters, depressed wells within said deck and winches within said wells for the purpose described.

10 15. A vessel of the character described, comprising a hull, removable turrets, bollards and smoke stack, upon the upper deck of said hull, adjustable hoisting means upon the deck adjacent the turrets, depressed wells within the deck adjacent the hoisting means, and power winches within the wells for furnishing the power to the hoisting

means, whereby the turrets, bollards and smoke stack may be removed from the deck and placed within the hull of the vessel.

16. A navigable vessel comprising a hull having a deck forming the upper wall thereof, a depressed well within the deck and extending within the hull and line operating winches within the well for operating mechanisms upon the deck.

In testimony whereof we hereunto affix our signatures in the presence of two witnesses.

ALEXANDER McDougall.
